tion of New Jersey

Application September 22, 1939, Serial No. 296,058

5 Claims. (Cl. 80—45)

This invention relates to sheet handling apparatus for rolling mills. It relates more particularly to sheet feeding and receiving mechanism for passing sheets back and forth as they are reduced in a rolling mill.

The invention will be described and illustrated in connection with the handling of sheets as they are being reduced in a typical 3-high rolling mill. The sheets or sheet bars are first fed through the mill from the roller's side between the middle roll and the bottom roll and are then returned from the catcher's side of the mill between the middle roll and the top roll and this process is repeated with appropriate intermediate adjustment of the roll passes, ordinarily accompanied by doubling of the sheets, until the sheet, pair or pack has been reduced to the desired extent. It is customary to employ feed tables and catching tables to handle the work as it is passed back and forth through the mill during reduction. Such tables ordinarily comprise endless work handling conveyors, the feed table feeding the sheets through the mill from the roller's side between the middle and bottom rolls and the catching table receiving the sheets as delivered from the mill at the catcher's side, elevating the same and feeding the same back to the roller's side between the middle and top rolls, whereupon they are received upon the feed table and fed again between the middle and bottom rolls.

Heretofore it has been customary to mount sheet handling tables of the type above referred to in operating position adjacent a mill where they are bolted down or otherwise fixedly positioned, the endless conveyor having fixed mounting relatively to the base of the table. When it is necessary to have access to the mill rolls, as in making roll changes, the tables have had to be unbolted or otherwise released from their fixed operating position and moved bodily away from the mill and after the roll change or other work on the mill has been completed the tables have had to be moved back into operating position and again fastened in place. Such a condition is, of course, highly undesirable, as much time and labor is required in unfastening the tables, moving them away from the mill, moving them back toward the mill and fastening them in position again. However, prior to the present invention this has always been done so far as I am aware.

I obviate the disadvantages of the prior practice in the art as referred to above by providing sheet handling tables which are permanently mounted adjacent the mill and which while so

5 mounted can easily be manipulated to clear the mill for roll changes, etc. I provide for moving the sheet handling portion of a table relatively to the base thereof to withdraw the sheet handling portion away from the mill without disturbing the mounting of the table. I also provide for driving the conveyor in such manner that the driving means is not disturbed or disconnected upon such withdrawal of the sheet handling portion of the table.

10 Other details, objects and advantages of the invention will become apparent as the following description of a present preferred embodiment thereof proceeds.

15 In the accompanying drawings I have shown a present preferred embodiment of the invention, in which

Figure 1 is an elevational view of a feed table;
Figure 2 is an elevational view of a catching table;

20 Figure 3 is a plan view of the feed table shown in Figure 1;

Figure 4 is a plan view of the catching table shown in Figure 2; and

25 Figure 5 is a vertical transverse cross-sectional view taken on the line V—V of Figure 2, parts being omitted for the sake of clarity.

Referring now more particularly to the drawings, there is shown diagrammatically a 3-high 30 rolling mill comprising a middle roll 2, a bottom roll 3 and a top roll 4. This is a typical 3-high mill with the middle roll of less diameter than the top and bottom rolls and the rolls may be mounted in any suitable housings provided with 35 screwdowns as well known in the art. As the present invention has nothing to do with the particular mounting for the rolls the roll housings are omitted from the drawings so that the apparatus which is the subject of the invention may 40 be the more clearly illustrated. The mill floor is designated at 5, the roll housings being mounted in a pit 6 and the feed table 7 and the catching table 8 being mounted respectively on bases 9 and 10 below the floor level. The feed table 7 and the catching table 8 are permanently mounted at 45 opposite sides of the mill. Their relative positions in elevation may be seen at a glance by positioning the sheet containing Figure 1 of the drawings to the right of the sheet containing Figure 2. Likewise the tables may be seen in their 50 relative positions in plan by positioning the sheet containing Figure 3 of the drawings to the right of the sheet containing Figure 4.

Referring first to the feed table 7, it comprises a pair of spaced links 11 both pivotally mounted

on a shaft 12 rotatably carried in bearings 13 fixed to the base 9. A shaft 14 extends through openings in the upper ends of the links 11 and also pivotally supports the right-hand end of a deck 15 viewing Figures 1 and 3. The deck 15 has adjustable side guides 16 between which the sheets pass. The sheets are advanced on the deck 15 toward the mill by a pair of endless chains 17. These chains are shown in Figure 3 and the upper reaches thereof run in channels 16a each containing a replaceable wear resistant liner 16b. In Figure 1 the chains 17 are not drawn in detail but their path of movement is indicated by a chain line similarly numbered. Each of the chains 17 passes about a driving sprocket 18 fixed to the shaft 12, an idler sprocket 19 carried by the shaft 14, an idler sprocket 20 carried by a shaft 21 at the left-hand end of the deck 15 viewing Figures 1 and 3, and idler sprockets 22, 23 and 24 carried beneath the deck as shown in Figure 1. Take-up mechanism for each of the chains 17 comprises a take-up sprocket 25 carried by a stud shaft 26 at the extremity of an arm 27 fixed to a shaft 28 carried in bearing brackets 45 connected respectively with the links 11. Also fixed to the shaft 28 is a pair of arms 29 to the extremity of each of which is pivoted at 30 a rod 31 carrying a collar 32 against which bears a coil spring 33. Each rod 31 is slidably mounted in a bracket 33a carried by one of the links 11 and against which the corresponding spring 33 bears. Thus through its spring 33, rod 31, arm 29, shaft 28, arm 27 and take-up sprocket 25 each of the chains 17 is maintained desirably taut.

As will be seen from the above description, the links 11 may pivot about the axis of the shaft 12 and the deck 15 may pivot about the axis of the shaft 14 and such pivotal movement, if reasonably limited in extent, will not change the paths of the chains 17 more than can be compensated for by the take-up mechanism above described. Moreover, such pivotal movement of the links 11 and/or the deck 15 can be effected without removing the table 7 from its base 9 and without disconnecting the driving means for the chains. Such driving means comprises a motor 34 having a shaft 35 which drives the shaft 12 through suitable driving connections including speed reducing mechanism 36. Regardless of the position of the links 11 and the deck 15 the chains 17 may be driven through the shaft 12 whose axis is fixed.

The mounting of the links 11 and the deck 15 as above described is utilized to permit movement of the deck away from the mill to clear the mill for roll changes and other work thereon. The deck is in part supported by an adjustable link 37 pivoted to the deck at 38 and pivoted at 39 to a bracket 40 fixedly carried by the base 9. The adjustable link 37 comprises opposed upper and lower link portions whose inner ends are threaded as shown at 41, such threaded ends cooperating with a worm operated turnbuckle 42 having an operating hand wheel 43. By means of the adjustable link 37 whose length may be altered by turning the hand wheel 43 the elevation of the left-hand end of the deck 15 may be adjusted as desired. A similar adjustable link 44 extends between and is pivotally connected with the shaft 28 and a bracket 46 fixedly carried by the base 9.

When the feed table 7 is in operation the links 11 and the deck 15 remain in fixed position with the roller 47 carried at the extreme left-hand

extremity of the deck viewing Figures 1 and 3 in the position shown in dotted lines in Figure 1. The table as shown in solid lines in Figures 1 and 3 is in the retracted or inoperative position where it clears the mill so that the mill rolls may be changed. The deck is moved toward and away from the mill simply by turning the hand wheel 48 which operates the worm operated turnbuckle changing the length of the adjustable link 44. Upon change in length of the adjustable link 44 the links 11 and 37 are caused to pivot about their respective fixed extremities 12 and 39. As above stated, the elevation of the left-hand extremity of the deck 15 is determined by the length of the adjustable link 37.

Thus the deck of the table 7 may at will be moved toward and away from the mill without disconnecting the table from its base and without disturbing the drive for the chains 17. The deck carries pivotally at its right-hand end a frame 49 carrying rollers 50 over which the sheets or sheet bars pass onto the upper reaches of the chains 17 when work is to be commenced thereupon. The frame 49 is normally in the lower or dotted position viewing Figure 1 but is raised to the solid line position when the deck is retracted from the mill so as to clear other mechanism which may be disposed immediately to the right of the feed table 7.

The structure of the feed table is such that it may be driven by a permanently mounted motor disposed below the floor level of the mill and connected directly with the driving shaft 12 without the use of any intermediate driving chains such as have been employed in sheet handling tables heretofore used.

The catching table 8 is similar to the feed table 7. It comprises a pair of spaced links 11' both pivotally mounted on a shaft 12' rotatably carried in bearings 13' fixed to the base 10. A shaft 14' extends through openings in the upper ends of the links 11' and also pivotally supports the left-hand end of a deck 15' viewing Figures 2 and 4. The deck 15' has adjustable side guides 16' between which the sheets pass. The sheets are received upon the deck 15' as they pass through the mill between the middle roll 2 and the bottom roll 3 and the right-hand end of the deck 15' is then raised to the position shown in Figures 2 and 4 to deliver the sheets back between the middle roll 2 and the top roll 4, as will presently be described. A pair of endless chains 17' similar to the chains 17 of the feed table are provided. These chains are shown in Figures 4 and 5 and the upper reaches thereof run in channels 17a each containing a replaceable wear resistant liner 17b. In Figure 2 the chains 17' are not drawn in detail but their path of movement is indicated by a chain line similarly numbered. Each of the chains 17' passes about a driving sprocket 18' fixed to the shaft 12', an idler sprocket 19' carried by the shaft 14', an idler sprocket 20' carried by a shaft 21' at the right-hand end of the deck 15' viewing Figures 2 and 4, and idler sprockets 22', 23' and 24' carried beneath the deck as shown in Figure 2. Take-up mechanism for each of the chains 17' comprises a take-up sprocket 25' carried by a stub shaft 26' at the extremity of an arm 27' fixed to a shaft 28' carried in bearing brackets 45' connected respectively with the links 11'. Also fixed to the shaft 28' is a pair of arms 29' to the extremity of each of which is pivoted at 30' a rod 31' carrying a collar 32' against which bears a coil spring 33'. Each rod 31' is slidably

mounted in a bracket 33b carried by one of the links 11' and against which the corresponding spring 33' bears. Thus through its spring 33', rod 31', arm 28', shaft 28', arm 27' and take-up sprocket 25' each of the chains 17' is maintained desirably taut. The driving means for the chains 17' comprises a motor 34' having a shaft 35' which drives the shaft 12' through suitable driving connections including speed reducing mechanism 36'.

The deck 15' is operated in its up and down pivotal oscillatory movement about the axis of the shaft 14' when the table 8 is in use and is partially supported by an adjustable link 37' pivoted to the deck at 38' and pivoted at 39' to a crank 51 carried by a shaft 52. The shaft 52 is mounted in bearings 52a and is periodically operated by a motor 53 through transmission mechanism 54, it being understood that suitable control means are provided for operating the motor 53 when desired.

An adjustable link 44' extends between and is pivotally connected with the shaft 28' and a bracket 46' fixedly carried by the base 10.

The mass of the deck 15' is partially supported by a pair of spring-balancing assemblies 55, one at each side of the deck. Each of these assemblies has upper and lower telescoping members 56 and 57, respectively, between which operates a compression spring 58. The member 56 is pivoted to the deck 15' at 59 and the member 57 is pivoted to the base 10 at 60. The purpose of the spring-balancing assemblies 55 is to reduce the weight which is alternately lifted and lowered by the crank 51 and its associated mechanism, thereby reducing the power required for lifting the deck and overcoming in part the tendency of the weight of the deck to accelerate the drive while lowering.

When the catching table 8 is in operation the links 11' remain in fixed position, the deck being oscillated by the crank 51 as above explained. When a sheet is delivered between the rolls 2 and 3 to the catcher's side of the mill the deck 15' is in its lower position and receives the sheet, the chains 17' then moving in the direction to carry the sheet or sheets away from the reducing rolls. The crank 51 is then rotated through 180° to raise the deck to its raised position as shown in Figure 2 when the chains 17' are reversed in direction to feed the sheet back to the roller's side of the mill between the rolls 2 and 4. The crank 51 is then rotated through another 180° to bring the deck to its lower position and the cycle is repeated.

The rolling operations are thus conducted for the desired number of passes between the working rolls, the final pass delivering finished sheets or bars to the catching table, this time to be discharged and piled instead of being returned through the mill. When work is thus discharged after being rolled it passes along the deck 15' from right to left viewing Figures 2 and 4 and over idler rollers 61 and is ejected by driven pinch rolls 62. Heretofore it has been customary for pinch rolls used for discharging the work to be continuously driven by a separate motor. In my apparatus, however, when the upper reaches of the chains 17' are moving toward the left viewing Figures 2 and 4 the pinch rolls 62 are driven to eject the work toward the left viewing these figures, this being accomplished by a chain and sprocket drive 63 (Figure 4) from the shaft 14'. An overrunning clutch 64 is provided for driving the pinch rolls 62 only when the upper

reaches of the chains 17' are moving from right to left viewing Figures 2 and 4. When the upper reaches of the chains 17' are moving from left to right viewing these figures the clutch 64 simply idles and the pinch rolls 62 continue by reason of their inertia to rotate idly in the same direction as that in which they are driven when the upper reaches of the chains 17' are moving from right to left. The pinch rolls are preferably journaled in anti-friction bearings, as, for example, ball or roller bearings, so that there will be very little friction tending to bring them to a stop when idling. Also the structure of the pinch roll system is such that the momentum of the rotating parts is great enough to keep the pinch rolls moving until the succeeding application of power thereto in normal operation of the mill. This saves the power necessary to start up the pinch rolls from rest or to continuously drive the same and also saves wear and tear on the pinch roll system, including particularly the sprocket chain, due to sudden and repeated application of power to start the same from rest. For example, the pinch rolls may be of such construction as to themselves act somewhat in the nature of flywheels or separate flywheels may be employed on the roll shafts. The structure described obviates using a separate motor for operating the pinch rolls and thus further reduces the cost of the apparatus and the cost of maintenance and operation thereof.

While I have shown and described a present preferred embodiment of the invention, it is to be distinctly understood that the same is not limited thereto but may be otherwise variously embodied within the scope of the following claims.

I claim:

1. Sheet handling apparatus for rolling mills comprising a support, an endless conveyor carried by the support and having a generally horizontally extending sheet supporting reach and another reach extending generally downwardly therefrom, a base fixed relatively to the mill floor, driving means for the conveyor mounted on said base, said driving means including a fixedly positioned driving shaft and a driving member carried by said shaft and engaging the generally downwardly extending reach of the conveyor, and adjustable length means extending between the base and a portion of the support for generally horizontally adjusting the position of the generally horizontally extending reach of the conveyor.

2. Sheet handling apparatus for rolling mills comprising a base fixed relatively to the mill floor, a support having a pivotal connection with the base, an endless conveyor having a generally horizontally extending sheet supporting reach carried by the support, driving means for the conveyor including a driving shaft coaxial with said pivotal connection and connections therefrom to the conveyor and normally stationary adjustable length means extending between the base and a portion of the support for generally horizontally adjusting the position of the sheet supporting reach of the conveyor.

3. A rolling mill feed table comprising in combination a movable chain conveyor having a substantially horizontally extending sheet supporting reach having one end adjacent the mill rolls, a fixed base, driving gear fixedly mounted on the fixed base including a sprocket engaging an extension of the conveyor chain below the table, a substantially vertical supporting link of fixed length pivoted to the table near the end away

from the mill rolls and pivotally connected to the fixed base about the axis of said sprocket, an inclined link adjustable in length pivotally connected to the conveyor and to said base whereby the conveyor may be shifted longitudinally and means supporting from said fixed base the end of the conveyor adjacent the mill rolls.

4. Sheet handling apparatus for rolling mills comprising a base fixed relatively to the mill floor, a support having a pivotal connection with the base and extending generally toward the mill rolls, an endless conveyor having a generally horizontally extending sheet supporting reach carried by the support, driving means for the conveyor including a driving shaft coaxial with said pivotal connection and connections therefrom to the conveyor, means extending between the base and part of the support near the mill rolls for partially supporting the support and normally stationary adjustable length means extending between the base and a portion of the support for generally horizontally adjusting the position of the sheet supporting reach of the conveyor.

5. Sheet handling apparatus for rolling mills comprising a sheet supporting conveyor having a generally horizontally extending reach one end of which is adapted to be positioned adjacent the mill rolls and a second reach extending generally downwardly from the first mentioned reach, a fixed base, rotary driving means mounted on the base and engaging said second mentioned reach of the conveyor whereby to drive the conveyor, a generally vertically extending conveyor supporting link pivoted to the conveyor adjacent the end of the first mentioned reach thereof disposed away from the mill rolls and pivoted to the base about the axis of the driving means, means extending between the conveyor and the base for shifting the first mentioned reach of the conveyor generally longitudinally and means also extending between the conveyor and the base for supporting the end of the first mentioned reach of the conveyor adjacent the mill rolls.

FRED H. FANNING.
